UNITED STATES PATENT OFFICE.

HENRY SUTCLIFFE, OF BROOKLYN, NEW YORK.

IMPROVEMENT IN NUMBERING-MACHINES.

Specification forming part of Letters Patent No. 95,282, dated September 28, 1869; antedated September 16, 1869.

To all whom it may concern:

Be it known that I, HENRY SUTCLIFFE, of Brooklyn, in the county of Kings and State of New York, have invented, made, and applied to use a certain new and useful Improvement in Numbering-Machines; and I do hereby declare the following to be a full, clear, and exact description of the said invention, reference being had to the annexed drawings, making part of this specification, wherein—

Figure 1 is a side elevation of my said machine, a part of the frame being removed. Fig. 2 is a front elevation of the machine. Fig. 3 is a side view of the upper portion of the machine with the rollers back upon the inking-table, and the head depressed for printing, and Fig. 4 is a sectional plan at the line $x x$ of Fig. 1.

Similar marks of reference denote the same parts.

This invention relates to a machine for printing numbers upon notes, checks, drafts, policies, or other business papers, or for the numbering of books or pages.

In the machines that have before been made, difficulty has been experienced in presenting large-sized sheets of paper or other material to the stamping mechanism, because the table extended to the frame, and if the sheets to be numbered were wider than the space between the impression-bed and the frame, they could not be stamped without being folded.

The nature of my said invention consists in a supporting and impression table, combined with a forked frame, one part of which supports said table, and the other part sustains the numbering mechanism, so that a space is left for the sheet that is being numbered to slide down between said forks of the frame, and thereby remain uninjured by folding, and in the most convenient position for handling while being presented to the numbering mechanism, and I provide a peculiarly-arranged inking-table to supply and work the ink of the inking-rollers.

In the drawing, a represents the table, that is supported by the rods b , that pass through holes in part of the frame of the machine, and said table may be raised and lowered as necessary.

The side frames of the machine are made with the forks or branches c and d , the fork c

supporting the table a and the impression-bed e , and the fork d supporting the head-frame f , that carries the slide-rod g , block h , and series of type, letter, or number wheels l .

The treadle m on the fulcrum 2 is connected by the rod n with the lever o , set upon a fulcrum, 3 , upon the frame f , so as to actuate the rod g and number-wheels, and press them down upon the paper or other material to be numbered or printed, and 4 is an adjustable stop to regulate the point to which the lever o and type-wheel l descend. The treadle m , rod n , and parts connected are returned to their normal position by the springs 5 and 6 .

The type-wheels l are made in any usual or desired manner, and the progressive motion to the type-wheels is given by the link o' , that is jointed to the frame f , and turns the wheels as the block h and number-wheels rise; hence the movement is in the same direction as that of the inking-rollers p q , as hereinafter mentioned.

Upon the block h are the fulcrums 7 of the crank-levers r , that are connected by the links s to the frame f , and t are shoe-pieces, carrying the inking-rollers p q . These shoe-pieces t are connected to the lever r by screws and slots 8 , so as to be adjusted properly to bring the ink-rollers into contact with the type-wheels, and 9 are set-screws for adjusting and holding the parts in position.

It will be understood that as the head-block and type-wheels move up from the position of Fig. 3 to that of Fig. 1, the type wheel or wheels are moved in the direction denoted by the arrow, Fig. 1, and the ink-rollers p q in passing off the table v move in the direction indicated by the arrow, and in the same direction as the types; hence there will be a perfect inking of the type, but the ink will not be scraped off the roller by the type, as is usual in numbering-machines where the surfaces of the types and rollers are moving in opposite directions when the ink is being applied; therefore the types in my machine will keep clean and give better impressions.

My inking-table v is set to rock upon the axis 19 , that carries the center 10 of said table, and the base 11 that carries the axis 19 is adjustable so as to set the ink-table at the proper point, and 12 is an adjustable stop to determine the inclination of the table, the contrac-

tile spring 13 keeping said table toward that stop 12.

Around beneath the table v is a circular range of ratchet-teeth, and the pawl 14 on the arm 15 is moved by the inclined bar 16 as the table is tipped into the position of Fig. 3, so as to take another tooth of the ratchet, and 17 is a contractile spring to draw the pawl 14 back to its normal position and give the table v a partial rotation after the rollers p and q pass off said table v .

By this arrangement of inking-table the ink will be thoroughly worked, and a small amount of ink applied to said table periodically, say every few hours, will furnish sufficient ink for said numbering-machine.

It will be understood that the sheet of paper or other material that is being printed will hang down between the forks c and d of the frame while being numbered toward the edge that is next to the operator, as illustrated by the blue line in Fig. 1, and that in consequence of this construction the inking-table can be near the type-wheel, and that large-sized

sheets of material can be numbered with great facility.

What I claim, and desire to secure by Letters Patent, is—

1. A numbering-machine in which the table, frame, and numbering-wheels are arranged and applied in the manner specified, so that the sheet of paper on which the impression is being made can hang down between the table and the frame supporting the numbering mechanism.

2. The revolving inking-distributing table v , set upon the axis 19, so that the same may be rocked by the contact of the inking-rollers p and q as they swing, said table being fitted with ratchet-teeth, and acted upon by a pawl and spring, substantially as set forth.

In witness whereof I have hereunto set my signature this 16th day of June, A. D. 1868.

HENRY SUTCLIFFE.
